UNITED STATES PATENT OFFICE.

GEORGE MANIERRE, OF MILWAUKEE, WISCONSIN.

BOX-CAR-LOADING APPARATUS.

1,226,553.

Specification of Letters Patent. Patented May 15, 1917.

Application filed October 21, 1914. Serial No. 867,792.

To all whom it may concern:

Be it known that I, GEORGE MANIERRE, a citizen of the United States, residing at Milwaukee, in the county of Milwaukee and 5 State of Wisconsin, have invented certain new and useful Improvements in Box-Car-Loading Apparatus, of which the following is a specification, reference being had to the accompanying drawing, forming a part 10 thereof.

This invention relates to box car loading apparatus and the objects of the invention are to improve loading apparatus in the manner to be hereinafter described and 15 claimed.

Referring to the drawings which accompany this specification and form a part hereof, which drawings illustrate an embodiment of this invention, and on which drawings 20 the same reference characters are used to designate the same parts wherever they may appear in the several views, Figure 1 is an elevation of box car loading apparatus, a part of a box car being shown in section; 25 and Fig. 2 is a plan view of the apparatus, a part of the box car being shown in section.

Referring to the drawings, the reference numeral 1 designates an upright member to which are secured bearings 2 and 3 for a 30 shaft 4. An arm 5 is hinged to shaft 4 and an arm 6 is hinged to arm 5. A yoke 7 is pivotally supported in the end of arm 6 and this yoke supports conveying mechanism which may be briefly described as composed 35 of the frame 8 pivotally supported by the yoke 7, the endless conveyer 9, the electric motor 10 for actuating the conveyer 9, and the hopper 11.

The reference numeral 12 designates a 40 fixed, inclined spout or chute leading from the source of supply of the material to be loaded. This chute is provided with two extensions 13 and 14. Extension 13 is revolvably supported about the end of chute 12. 45 In the specific construction illustrated the extent of revolution is limited but it is ample for the specific construction illustrated. The end of the extension 13 adjacent chute 12 is flared or enlarged to permit of its being 50 swung or revolved and this end is supported from chute 12 by the bolt 15 which serves as a pivot for the swinging movements of the extensions. A curved track 16 is rigidly supported from chute 12, the curvature being the arc of a circle struck from bolt 15 as a center. In the construction illus-

trated by the drawings, this curved track is made from channel iron so that the wheels 17 and 18 can run on either the upper or lower flange and thus prevent the outer end 60 of the extension 13 from being displaced to any material extent either up or down. The wheels 17 and 18 are carried on the ends of bars 19 and 20 secured to the extension 13. Track members 21 and 22 are connected 65 with bars 19 and 20 and with the outer end of extension 13 and extend downwardly and then horizontally and trolleys 23 and 24 travel on these track members. The extension 14 is pivotally supported on the trolleys 70 at a point always inside the end of the extension 13 and is counterbalanced by the weight 25 on the bars 26. Sprocket chains 27 and 28 are fastened to the trolleys 23 and 24 and run over sprocket wheels 29 and 30 75 fast on shaft 31 and sprocket wheels 32 and 33 adjustably secured to the extension 13. The chain wheel 34 fast on shaft 31 when turned by the chain 35 will move the trolleys 23 and 24 and the extension 14 either forward or back on the track members 21 and 22. 80

The outer end of the extension 14 is contracted in width as clearly shown by Fig. 2 of the drawings, so that the conveyer 9 can be moved farther toward the ends of the car 85 to avoid the necessity of throwing the material by the conveyer to fill the ends of the car.

The bottom of the extension 14 is curved upwardly at its outer end and toward its 90 sides to conform to the conical shape of the hopper 11, into which it projects.

The operation of the apparatus is clear from the foregoing description of the construction. The extension 14 can be run into 95 a car door or back out of the way easily by one man and the extensions 13 and 14 can be easily revolved or swung horizontally by one man about the pivot bolt 15, to feed the material into the hopper 11 when the arm 6 100 is swung to move the conveyer 9 either toward or away from the end of the car.

What is claimed is:

1.. The combination with a chute of an extension revolvably supported therefrom by a 105 bolt at one end, a curved track fixed to a suitable support, and means fixed to said extension and adapted to travel on said track to prevent the other end of the extension from being displaced to any material 110 extent either up or down.

2. The combination with a chute of an

extension revolvably supported therefrom by a bolt at one end, a curved track fixed to a suitable support, means fixed to said extension and adapted to engage with said track 5 to prevent the other end of the said extension from being displaced to any material extent either up or down, track members secured to said extension, and a counter-

balanced extension adapted to be moved back and forth on said track members.

In witness whereof I hereto affix my signature in presence of two witnesses.

GEORGE MANIERRE.

Witnesses:

FRANK E. DENNETT,
FRED PALM.
